ATTORNEY

UNITED STATES PATENT OFFICE.

CHARLES AGUSTUS WELCH, OF COLUMBUS, NEBRASKA.

MATTRESS CARRIER.

Application filed September 10, 1924. Serial No. 736,917.

To all whom it may concern:

Be it known that I, CHARLES A. WELCH, a citizen of the United States, residing at Columbus, in the county of Platte and State 5 of Nebraska, have invented a new and useful Improvement in Mattress Carriers, of which the following is a specification.

This invention relates to mattress carriers.

Mattresses are usually very bulky and 10 unwieldy and cannot be easily handled by one person or even two persons by reason of the fact that no proper hold can be obtained thereon which will not either slip or cause the tearing of the mattress.

Handles have been permanently secured 15 to mattresses to overcome this difficulty, but they are not desirable, as the handles destroy the appearance, and in some cases actually defeat the purpose of the mattress, which is 20 to provide a soft even surface upon which to lie. Large and complicated carrying devices which enclose the entire mattress have been devised, but are fully as unwieldy as the mattress itself, and are furthermore too 25 costly for the average housewife.

The object of this invention is to provide 30 a simple and light carrier by the use of which a mattress, or like article, of considerable weight and size may be readily carried by a single person.

A further object of the invention is to 35 provide a carrier of this character which is adjustable so as to accommodate it to the user or the article to be carried.

With these and other objects in view, as 40 will appear as the description proceeds, this invention consists of the novel features of construction, combinations of elements, and arrangements of parts, hereinafter to be fully described and claimed.

A full and complete understanding of the 45 invention may be obtained from a consideration of the following detailed description, taken in connection with the accompanying drawing forming a part of this specification, it being understood that while the drawing shows a practical form of the invention, the latter is not to be confined to strict conformity with the showing thereof, but may 50 be changed and modified, so long as such changes and modifications mark no material departure from the salient features of the invention, as specifically pointed out and claimed.

In the drawing, in which similar reference 55 characters indicate similar parts throughout the several figures:

Figure 1 is a perspective view illustrating 60 a person carrying a mattress with the carrier of the invention;

Figure 2 is a horizontal sectional view of the carrier;

Figure 3 is a vertical sectional view thereof; and

Figure 4 is an enlarged perspective view 65 of the buckle showing, by dotted lines, the association of portions of the carrier therewith.

The carrier 1 comprises a strap 2 of leather or like material, to one end of which 70 is permanently secured, by rivets 3, the closed strap hand loop 4, which extends at right angles to the strap 2. Centrally of the strap 2 is provided a row 5 of spaced apertures 6, which extends from adjacent 75 the end 7 toward the other end of the strap 2, and each of the apertures is adapted to receive the tapered pin or post 8 of the buckle 9, to determine the length of that portion of the strap 2 between the loops 4 80 and 10.

The buckle 9 comprises a pair of curved arms 11 spaced apart and connected by integral bars 12 at each end, and 13 at the center, and has the post 8 extending from the 85 center of bar 13, between the end bars 12.

The closed loop 10 has one of its sides passing through the buckle between the bars 12 and bar 13, and is therefore permanently 90 assembled with the buckle. The loop is also apertured as at 14 to receive the post 8. The loop 10 and buckle 9 may be quickly secured to the strap 2 by removing the post 8 from aperture 14, which is done by drawing the portion of loop 10 between the bars 12 95 toward the other side of the loop, then passing the end 7 between loop 10 and the bar 13 and engaging the post in the appropriate aperture 6, and finally returning the portion of loop 10 to its position with the upper portion of the post 8 disposed within aperture 14.

In the practice of this invention, the housewife first rolls the mattress up without removing it from the springs which 105 support it, inserts the end 7 of the strap 2, from which the loop 10 and buckle 9 have been removed, centrally under the mattress

and pushes it through to the other side. She there secures the buckle 9 and hand loop 10 in the desired position, as has been described, and grasping one handle in each hand, raises the mattress to the position illustrated in Figure 1 of the drawing, in which position the body aids in supporting the weight of the mattress and it can be carried without difficulty. Obviously the device may be used with the loops extending either toward or away from the article being carried, or, as loop 10 may be disposed on either side of the strap 2, one loop may be turned toward and the other away from the article as desired, although experience has taught that the use of the device as shown is most convenient.

What is claimed is:—

1. A device of the class described comprising a strap having a row of spaced apertures extending from adjacent one end toward the other end thereof, a hand loop secured to said other end, a buckle, a second hand loop detachably associated with said buckle and

projecting transversely therefrom, and means on said buckle engageable selectively with the apertures for holding said second loop in adjusted positions on the strap, whereby upon removing the second loop the strap may be inserted under a mattress and the said second loop reapplied to the strap and used in cooperation with the first hand loop to carry the mattress.

2. A mattress carrier comprising a strap, a hand loop on one end of said strap, a buckle having a pair of spaced arms, a central bar, and a pair of end bars connecting said arms, a second loop having a side passing between the end bars and the central bar, said strap passing between the central bar and said second loop, and co-operating means on said strap and buckle for securing said second loop in adjusted positions on the strap.

In testimony, that I claim the foregoing as my own, I have hereto affixed my signature.

CHARLES AGUSTUS WELCH.
